UNITED STATES PATENT OFFICE

2,554,596

SUPERVISION CIRCUIT FOR TELEGRAPH SYSTEMS

Antonie Snijders, The Hague, Netherlands

Application December 17, 1947, Serial No. 792,246
In the Netherlands September 14, 1946Section 1, Public Law 690, August 8, 1946
Patent expires September 14, 1966

3 Claims. (Cl. 178—69)

1

The invention refers to a supervisory arrangement for a teleprinter communication system.

The object of the invention is to provide a receiving arrangement responsive to a signal consisting of a "mark" start element followed by five "mark" elements. Ordinarily teleprinters are not responsive to this "five-mark-signal."

Conversely, the arrangement of the present invention is not responsive to the signals which actuate the teleprinter.

For selective separation the arrangement according to the invention comprises a group of a condenser and a high ohmic leak resistance as a timing device. The leak resistance is shunted by a diode causing the timing device to act slowly for one current direction, but rapidly for the opposite direction of the current.

The voltage across the condenser serves as a bias for a three-electrode vacuum tube, the terminals of the condenser being connected to the cathode and the grid, respectively.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

The only figure is a wiring diagram of an arrangement according to the invention.

Referring to the drawing, a telegraph battery has its midpoints grounded and is bridged by two potentiometer resistances R_3 and R_4 , the junction of the resistances R_3 and R_4 being formed by a point Z . Point Z is connected to a high ohmic resistance R_1 and the cathode of a diode D which bridges the resistance R_1 by having its anode connected to a point Y being the junction of resistance R_1 and a condenser C_1 the other side of which is formed by a point X connected to the cathode of a three-electrode vacuum tube B . The grid of tube B is connected by a resistance R_2 to the point Y and the anode of diode D . Point X is connected to the armature a of a signal reception relay A . Armature a moves between two stationary contacts connected, respectively, to the positive and negative battery terminals. In the anode circuit of tube B is inserted a supervisory relay AR having two armatures ar^1 and ar^2 . Armature ar^1 is connected to the negative battery terminal over a resistance R_5 and a switch S which may be hand-operated, and the contact with which ar^1 cooperates is connected to the terminal of relay AR which is connected to the anode of tube B . Armature ar^2 is connected in series between the negative battery terminal and a supervisory

2

circuit SC the other terminal of which is connected to the positive battery terminal.

The operation of this device is as follows:

The condenser C_1 and the resistance R_1 are connected in series and form a time delay circuit for tube B , resistance R_1 being shunted by the diode D . The operation of tube B depends on the voltage difference between the points X and Y . In the position shown in the drawing, 10 the relay armature a , which is controlled by the signal reception relay A , connects point X to the positive battery terminal e. g. to +60 volts. Point Y has the same potential as point Z , which is determined by the values of potentiometer 15 resistances R_3 and R_4 , and is negative with respect to the potential of point X . For instance, point Y may have a potential of -20 volts, i. e. 80 volts less than the potential of point X .

When a signal arrives, the start element causes 20 relay armature a to reverse, and the potential of point X is shifted by 120 volts from 60 to -60 volts.

At first point Y tries to follow the change of 25 voltage of 120 volts, i. e. its voltage is changed to a value near -140 volts, but at once a leaking current begins to flow through resistance R_1 , which restores the potential of Y to the initial value of -20 volts. The diode D is in blocking position for this current direction.

30 While changing its potential from approximately -140 volts to -20 volts point Y passes the potential -60 volts of point X , and from this moment onwards the grid of tube B is positive with respect to the cathode. The time delay with 35 which this happens can be adjusted very accurately, much more accurately than it could be achieved with an arrangement based on the end value of the condenser voltage which is only reached asymptotically.

40 This enhanced accuracy is useful as will be clear from considering that, when utilized for the normal five-unit code, the tube B must not become conductive before 100 milliseconds, and not later than 120 milliseconds after the beginning 45 of the start element. In practice the margin between these tolerances is reduced to a much narrower interval, owing to various technical deviations from the theoretical value which are unimportant for the present disclosure.

50 It is an important advantage of the present invention over other arrangements proposed for similar purposes, that the accuracy of the arrangement is widely independent of battery voltage.

The potentiometer resistances R_3 and R_4 can be equal to each other so that point Z assumes ground potential without being grounded directly.

55 Direct grounding of point Z , without providing the potentiometer resistances R_3 and R_4 , is

theoretically possible but is not preferred, because the time delay in operation of the tube B is in such an arrangement dependent on the battery voltage and on the symmetry of the battery.

Any of the signals to which the teleprinter is responsive, comprises at least one "space" element within 100 milliseconds after the start. This element causes the armature a to move back to the positive battery voltage, making the potential of point X +60 volts. The voltage between points Y and Z changes its size and the diode D becomes conductive, making the potential of point Y rapidly equal to the potential of point Z. The term "diode" is understood to include vacuum tube diodes, rectifier cells, resistors the resistance value of which depends on the temperature, and the like.

The arrangement is now prepared for the next signal.

The "five-mark signal" to which the described arrangement responds is not used for the teleprinter, because otherwise every line current interruption would be printed.

The tube B becomes conductive when 100 milliseconds after the start element the fifth "mark" arrives. The anode current energizes the supervisory relay AR, having an armature ar_2 to actuate a monitor or supervisory circuit SC. Holding armature ar_1 keeps thereby AR in operation even if tube B should become non-conductive again by the stop element of the signal. Relay AR can be restored to normal by interrupting the holding circuit by the switch S.

The supervisory circuit SC can serve for any convenient purpose which has no relation to the invention proper. For example it may start a visual and/or audible alarm (not shown), call a receiver for special messages (e. g. time signals transmitted in five-unit code), give a closing signal, etc.

The battery shown in the drawing can be the same as that serving the teleprinters. For that purpose its midpoint is grounded, but for the present invention the ground connection is not essential. With a common battery serving both the teleprinter and the above described device, relay A and its armature a may also be utilized for both these purposes. For this reason the normal or "space" position is shown in the drawing with positive battery voltage on the armature a , in accordance with standard teleprinter practice. The resistances R_2 and R_5 protect the tube B against excessive amperages.

It will be understood that each of the elements described above, or two or more together, may also find a useful application in other types of devices for receiving special signals differing from the types described above.

While I have illustrated and described the invention as embodied in a device for receiving special signals in a teleprinter code, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the

meaning and range of equivalence of the following claims.

1. A device for receiving special signals in a teleprinter code, comprising in combination, a D. C. source; means for defining a point having a third potential between the terminal potentials of said D. C. source; a receiving relay having a movable armature; two stationary contacts cooperating with said armature and being connected, respectively, with the terminals of said D. C. source; a condenser and a high ohmic resistance connected in series between said armature of said receiving relay and said point having a third potential; a diode connected in shunt to said high ohmic resistance; a vacuum tube having at least an anode, a cathode and a grid, said cathode and said grid being connected, respectively, to the terminals of said condenser; a supervisory relay connected in the anode circuit of said vacuum tube and having an armature; and a supervisory circuit controlled by said armature of said supervisory relay.
2. A device for receiving special signals in a teleprinter code, comprising in combination, a D. C. source; a potentiometer connected across said D. C. source and having a tap; a receiving relay having a movable armature; two stationary contacts cooperating with said armature and being connected, respectively, with the terminals of said D. C. source; a condenser and a high ohmic resistance connected in series between said armature of said receiving relay and said tap of said potentiometer; a diode connected in shunt to said high ohmic resistance; a vacuum tube having at least an anode, a cathode and a grid, said cathode and said grid being connected, respectively, to the terminals of said condenser; a supervisory relay connected in the anode circuit of said vacuum tube and having an armature; and a supervisory circuit controlled by said armature of said supervisory relay.
3. A device for receiving special signals in a teleprinter code, comprising in combination, a D. C. source; means for defining a point having a third potential between the terminal potentials of said D. C. source; a receiving relay having a movable armature; two stationary contacts cooperating with said armature and being connected, respectively, with opposite current source potentials; a vacuum tube having a cathode, a grid and an anode; a condenser, said armature of said receiving relay and said cathode of said vacuum tube being commonly connected to one terminal of said condenser; a high ohmic resistance, said point having a third potential being connected to one terminal of said high ohmic resistance, the other terminals of said condenser and of said high ohmic resistance being commonly connected to said grid of said vacuum tube; a diode connected in shunt to said high ohmic resistance; a supervisory relay connected in the anode circuit of said vacuum tube and having an armature; and a supervisory circuit controlled by said armature of said supervisory relay.
